DESIGN FOR A RADIATOR FRONT

Fred M. Young, Racine, Wis.

Application April 14, 1938, Serial No. 76,502

Term of patent 3½ years

To whom it may concern:

Be it known that I, Fred M. Young, a citizen of the United States, residing at Racine, in the county of Racine and State of Wisconsin, have invented a new, original, and ornamental Design for a Radiator Front, of which the following is a specification, reference being had to the accompanying drawing, forming a part thereof.

Fig. 1 is a side elevation of a radiator front showing my new design.

Fig. 2 is a front elevation of the design shown in Figure 1.

Fig. 3 is a top view of the design in Figures 1 and 2.

I claim:

The ornamental design for a radiator front, as shown.

FRED M. YOUNG.
